INVENTOR

E. M. Maynard Lindley.

UNITED STATES PATENT OFFICE.

ETTA MARGUERITE LINDLEY, OF NEW YORK, N. Y.

DESIGN FOR A BICYCLE-BOOT.

SPECIFICATION forming part of Design No. 26,876, dated April 13, 1897.

Application filed December 30, 1896. Serial No. 617,617. Term of patent 3 $\frac{1}{2}$ years.

To all whom it may concern:

Be it known that I, ETTA MARGUERITE LINDLEY, a citizen of the United States, residing in the city, county, and State of New York, 5 have invented and produced a new and original Design for Bicycle-Boots, of which the following is a specification, reference being had to the accompanying drawing, forming part thereof.

10 The drawing is a side elevation of my newly-designed boot, and this one view is deemed sufficient to fully illustrate my design.

15 The leading features of my design consist in a large trapeziform or irregular panel upon each side of the boot-leg of ornamental open or net work and also in transverse bands en-

circling the leg immediately above and immediately below the ankle-joint.

In the drawing, A represents the boot-leg; B, the ankle portion; c c c, the transverse 20 bands, and D represents the panel of open or net work, forming a large portion of the boot-leg.

What I claim as my design, and desire to secure by Letters Patent, is—

25 The design for a bicycle-boot substantially as herein shown and described.

ETTA MARGUERITE LINDLEY.
